UNITED STATES PATENT OFFICE.

ARTHUR P. STEWARD, OF WASHINGTON, D. C., ASSIGNOR OF TWO-THIRDS
TO T. L. FRACKER AND WILLARD FRACKER, BOTH OF SAME PLACE.

PORABLE OVEN.

SPECIFICATION forming part of Letters Patent No. 317,878, dated May 12, 1885.

Application filed March 25, 1885. (No model.)

To all whom it may concern:

Be it known that I, ARTHUR P. STEWARD, a citizen of the United States, residing at Washington, in the District of Columbia, have invented a new and useful Improvement in Portable Ovens, of which the following is a specification.

My invention relates to improvements in portable ovens, and is designed as an attachment to the portable stove for which Letters Patent were granted to Nathan O. Bond, dated April 7, 1885, and numbered 315,383.

Said invention consists of an oven constructed as hereinafter pointed out in the claims.

Referring to the drawings, Figure 1 is a side elevation showing the ordinary stove, the portable stove, and the oven mounted thereon. Fig. 2 is a vertical longitudinal section of the same. Fig. 3 is a view showing the portable stove and oven in section, a portion of the oven being broken away to expose the subjacent parts. Fig. 4 is a view in perspective of the combined flue and cut-off from beneath.

A represents the top plate of an ordinary stove, having the pot-holes B. C is the combustion-chamber, and D the flue-extension of the portable stove, the latter communicating with one of the pot-holes of said ordinary stove, so that the products of combustion may pass through its flues and into the chimney, the air to support combustion being admitted through the draft-opening a in the front wall of said portable stove, all as set forth in the patent referred to.

E is the oven, having double walls b c on four sides, which form flues d e f g around the same, and which are constructed of sheet metal or other suitable material. The bottom 40 of the outer casing has an opening, h, which coincides with the hole i in the top of the portable stove. The flue g has an extension, j, which depends sufficiently far below the oven to connect with the flue-extension D, as shown in the drawings, the outer wall, k, being continued at right angles to the same to form the plate l, which constitutes a cover for the flue-extension D. The inner wall, m, of said flue is continued downward through the 45 flue-extension, and is also bent at right angles

to said flue, but in a direction opposite to that of the plate l, thus forming the tongue n, which serves not only to hold the oven in place, but, together with the inner wall, m, to separate the main portion of the flue-extension D from the passage o, which connects it with the combustion-chamber C. The flue j, its rear wall, m, and the tongue n, in the particular construction shown, constitute what I term a "combined flue and cut-off." 55

It will be seen that by reason of the curved form of the wall of the flue-extension the flat wall m does not entirely close the passage o, but leaves a draft-opening, p, through which air may pass to support combustion in the 60 chamber C. By this construction, and by reason of the opening a at the front of the portable stove, air is admitted to the burning fuel on two sides thereof. The combustion is thus quickened and equalized and the retardation 65 of the draft by reason of its circuitous course around the oven compensated for.

A damper, q, closes the lower flue, d, at the end which adjoins the flue g, so that the products of combustion may be compelled to pass 70 around the oven. By opening the said damper the products will be permitted to pass through the flue d to the flue-extension without circulating around the oven. I am thus enabled to regulate the temperature of the air within 75 the same at pleasure.

A great advantage of constructing the combined flue and cut-off in the manner shown is that it is applicable to flue-extensions of different sizes, which are necessary in the manufacture of the portable stove, as the pot-holes of ordinary stoves are of different diameters. Whatever the size of the extension-flue, the combined flue and cut-off is moved as far as possible in the direction of the opening o, thus 80 bringing the edges of the plate m in contact with the inner walls of the flue-extension on either side, and, together with the tongue n, closing the passage for the products of combustion. 85

F is a damper, which is located in the combustion-chamber C, being intended, as set forth in the patent referred to, to throw the products of combustion against the rear wall of the said chamber as they pass to the opening 90 95 100

o during the ordinary operation of the portable stove. When the oven is in use, however, the products of combustion do not escape through said opening o, but pass upward 5 through the hole i in the combustion-chamber. At such a time the opening o serves another than its usual purpose, constituting then a conduit for the auxiliary supply of air referred to, which is admitted to the rear of the 10 fire through the opening p. The damper F, when in the position shown by the full lines, deflects the current of air upward to the point of flame within the chamber C, thus causing more perfect combustion and a hotter flame. 15 The said current of air is also heated by contact with the hot damper F and the adjoining walls, and produces the effect of a hot blast, making the combustion still more perfect. By turning the damper F as shown in 20 dotted lines the air is directed to the base of the fuel in the same manner as that which enters through the opening a, and effects the usual result.

The flue j is preferably made separable from 25 the oven, as shown, so that the combined flue and cut-off may be readily detached and placed in the oven during transportation, or when not in use. Such construction also renders the oven more easy of attachment, the 30 combined flue and cut-off being first placed in position and the oven afterward connected therewith.

The oven and its combined flue and cut-off 35 virtually constitute one and the same article, being, as stated, made separable only for convenience.

In using the apparatus a few sticks of kindling or of other light wood are placed in the chamber C and ignited, the flame and products of combustion therefrom passing through 40 the flues d e f g (or through the flue d alone, according to the position of the damper q) and into the ordinary stove by way of the flue j, as shown by the arrows. The top wall of 45 the oven is thus rendered sufficiently hot to heat a tea-kettle or tea-pot placed thereon.

The plate l, being flexible, may be bent upward at the end, as shown by the dotted lines in Fig. 2, to admit air to the flue-extension 50 for the purpose of retarding the draft.

Having fully described my invention, what I desire to claim and secure by Letters Patent is:—

1. An article of manufacture consisting of 55 a portable oven having double walls constituting a flue-space, said oven having an opening into the flue-space at one end, a flue at the opposite end communicating with the flue-space and extending down below the bottom 60 of the oven, said flue having its front and rear walls extending at an angle in opposite directions, whereby said flue may connect with an opening in a stove, and exclude connection with an aperture, substantially as and for the 65 purposes set forth and described.

2. An article of manufacture consisting of a portable oven having double walls constituting a flue-space, the said oven having an opening into the flue-space at one end, and provided at the other end with a flue communicating with the flue-space and extending down below the bottom of the oven, said flue having a plate attached thereto and a flange extending below the end of the flue, substantially as described. 70

3. An article of manufacture consisting of a portable oven having double walls constituting a flue-space, said oven being provided with an opening into the flue-space at one end, and having at the opposite end a flue communicating with the flue-space and extending down below the oven, said flue provided with a plate and having its inner wall extending below the flue and bent at an angle thereto, substantially as described. 80

4. An article of manufacture consisting of a portable oven having double walls which constitute a flue-space, said oven having an opening into the flue-space at one end, and having a flue at the opposite end communicating with the flue-space and extending down below the oven, said flue having a plate attached to its outer wall, and having its inner wall extending below the end of the flue and bent in an opposite direction to the plate, substantially 95 as described.

5. An article of manufacture consisting of a portable oven having double walls constituting a flue-space around a heating-chamber, said oven having an opening into the flue-space at one end, and a flue at the opposite end communicating with the flue-space, a damper between the two openings into the flue-space, the said flue extending down below the oven and having a plate attached thereto, 100 and a flange extending below the end of the flue, as and for the purpose set forth and described.

6. The combination of the portable stove having the combustion-chamber C, apertured at i, and extension-flue D, with the double-walled oven E, having the opening h and the flue j, said flue being provided with plates, substantially as described, for cutting off communication between the flue D and the combustion-chamber and the outer air, substantially 115 as described.

7. The combination of the portable stove having the combustion-chamber C, apertured at i, and extension-flue D, with the double-walled oven E, having the opening h and the flue j, said flue being constructed, substantially as described, to cut off direct communication between the chamber C and the flue D, substantially as described. 120
